Samuel H. Ransom, Albany, New York.
Letters Patent (Design No. 106) dated 5th January 1847.

The schedule referred to in these Letters Patent and, making part of the same.

To all whom it may concern; Be it known that I, Samuel H. Ransom of Albany in the County of Albany and State of New York, have invented or produced a new design for an Ornament at Parton Stone, and I do hereby declare that the following is a full, clear, and exact account of the same, reference being had

Des. 106

24

To the accompanying drawings making part of this specification Fig. 1. exhibits a perspective view of a stone after my design - Fig. 2, exhibits an enlarged view of the upper portion of the stone, the front & rear being similar. Fig. 3 represents the front & rear of the firebox. The ends are filled by the panel as and ornamented with the same border. The molding *bb* is continued entirely around the stone. The stone is in drawing, but half the front is exhibited, the other half being similar & symmetrical. Fig. 4. shows the scroll of the heart plate and a portion of its border. The ornaments are all in the style of Louis XIV and although not easily described in words, are fully represented in the drawings.

What I claim as my invention and desire to secure by letter patent is, the combination and arrangement of ornamental figures forming a design for an ornamental hearth stone as herein shown and described.
